CLAIM

The ornamental design for a two piece pouring shield for a mixer, as shown and described.

DESCRIPTION

FIG. 1 is a perspective view of a two piece pouring shield for a mixer showing my new design;

FIG. 2 is a top plan view thereof;

FIG. 3 is a side elevational view thereof, the opposite side being a mirror image;

FIG. 4 is a front elevational view thereof; and,

FIG. 5 is a rear elevational view thereof.

The bottom is not shown because it is unornamented.
